UNITED STATES PATENT OFFICE.

JOHN W. MULDOON, OF NEW YORK, N. Y.

REINFORCED CONCRETE CONSTRUCTION.

No. 874,226.

Specification of Letters Patent.

Patented Dec. 17, 1907.

Application filed June 27, 1907, Serial No. 381,045.

To all whom it may concern:

Be it known that I, JOHN W. MULDOON, a citizen of the United States, and a resident of the city of New York, borough of Manhattan, in the county and State of New York, have invented a new and Improved Reinforced Concrete Construction, of which the following is a full, clear, and exact description.

10 This invention relates to certain improvements in reinforced concrete construction, and more particularly to means for building walls, columns, girders, and floors, and involves certain improvements over the invention disclosed in my previous application, Serial No. 366,282, filed April 4, 1907.

In structures built in accordance with my invention I do not employ any sidings or frames to support the concrete, but provide 20 reticulated metal baskets of the desired shape and form, and build up the walls, columns, &c., by placing a first row or series of baskets in position, filling them with concrete, placing thereon a second series of 25 baskets, filling them with concrete, and repeating the operation until the structure acquires the desired height, the particular shape and size of the baskets being dependent upon the position in the wall and the 30 nature of the structure being built up.

The invention consists in certain features of construction and combinations of parts, all of which will be fully set forth hereinafter and particularly pointed out in the claims.

35 Reference is to be had to the accompanying drawing, forming a part of this specification, in which the figure is a perspective view of a portion of a structure built up in accordance with my invention.

40 The wall, illustrated is built as set forth in my previous application—above referred to and involves the use of a plurality of rectangular open-ended, open-topped, reticulated metal baskets 10, each of a width 45 slightly less than the width of the completed wall. A single row of these baskets are then placed end to end in the desired position and filled with concrete. Before the concrete has time to harden, a second row 50 of baskets is placed in position and the bottoms of the second row settle into the concrete filling the first row. The second row is then filled with concrete which unites with that in the series of baskets below, and the wall is ready for the third row of baskets. 55 The same principle is employed in construct-

ing the columns, only the baskets 11, which are employed, are preferably square and have four closed sides, the baskets differing from those employed in the construction of 60 the walls, in that the latter have open ends.

When the walls and columns have been built up to the height of the first story and it is desired to construct girders connecting the columns and the walls for supporting the 65 floors, I employ baskets of three different types, 12, 13 and 14, of such form as to provide girders integral with the walls and columns, and provide floor supports. The baskets 12 of one type, namely, those superimposed upon the columns, are constructed with a main body portion 15 of the same area in cross section as the baskets 11 forming the columns, and having four sides and an open top similar to said column baskets. 70 Each of the baskets 12 is provided with open-topped, open-ended branches 16 extending outward at the desired angles from the sides of the body portion, said baskets being of the desired width and height to 75 form the girders, and being of a length equal to one-half the distance from one column to an adjacent column or an adjacent wall. At the base of each of the girder-forming extensions 16, I provide transverse reinforcing bars 17 to prevent the top from spreading, and similar reinforcing bars 18 may be employed along the length of the extension. For further reinforcing the girder forming extensions 16, I provide reinforcing bars 19, each of which extends along the top of one side of one extension to the central body portion 15, then along the adjacent side of the body portion to the next extension, and terminates at the outer extremity of said last-mentioned girder-forming extension. The top of each column is capped by a basket of the form above described, and the meeting ends of the girder-forming extensions of adjacent baskets 12 100 are secured together in any suitable manner. If desired, the ends of the reinforcing bars 19 may be provided with loops 20 for the reception of suitable clips or fastening means.

In the walls at the same elevation as the baskets 12 and in alignment with the girder-forming extensions 16 of said baskets, I provide baskets 13, substantially T-shaped in form and having a body portion 21 substantially identical with the baskets 10 forming the wall. Extending out from an opening in the side of the body portion there is

provided a girder-forming extension 22, similar to the girder-forming extension 16 in alinement therewith and coöperating with said last-mentioned extension to form a girder. The extensions 22 and 16 terminate in open ends adjacent each other and are rigidly secured together in any suitable manner.

When the baskets 12 and 13 have been 10 placed in position, their ends secured together, and the row of baskets 10 placed in alinement with the body portions 21 of the baskets 13, the said baskets are filled with concrete in the same manner as were the 15 baskets previously placed in position. The body portions of the baskets 12 and 13 form a portion of the column and wall, and the extensions from said body portions form the girders connecting the column and wall. 20 When these baskets have been placed in position and filled, a third type of basket 14 is employed to form the floors. Each of these baskets has an open-ended body portion 23 substantially similar to the baskets 25 10 and the body portion 21 of the baskets 13, but extending outward from the basket and in alinement with the bottom thereof, there is provided an extension 24 of a width equal to the length of the basket, and of a 30 length substantially equal to the length of the girders. This extension may, if desired, be formed of heavier wire, and in any event is bordered by reinforcing bars 25 integral with the bottom of the body portion. These 35 baskets are placed in position with the body portion forming a part of the wall and the extensions 24 leading across the space between the wall and an adjacent girder parallel thereto. The body portion of these 40 baskets is then filled with concrete to unite with the concrete of the baskets below, and a thin layer of concrete is spread upon the extensions 24 to form the floor of the building. Above the body portions of the baskets 45 14 and 12 are then placed other series of baskets 10 and 11, and the walls and columns are continued upward to the next floor, at which point the baskets of the type above described are inserted to form a second series of girders and a second floor. 50 To conceal the wire mesh forming the walls of the several baskets, the sides of each column and the face of the walls are preferably provided with a coating 26 of cement mortar which firmly adheres to the rough surface of the baskets.

Having thus described my invention, I claim as new and desire to secure by Letters Patent:

60 1. A reinforced concrete column, comprising a plurality of reticulated metal baskets placed one upon the other and each filled with concrete after having been placed in position and before the next successive basket is placed in position.

2. The method of forming reinforced concrete columns, consisting in placing in the desired position, an open-topped metal basket, filling the same with concrete, superimposing thereon a second basket having a 70 reticulated bottom, filling said second basket with concrete, whereby the concrete in one basket unites through the openings in the bottom with the concrete in the basket below, and repeating the operation until the 75 desired height is attained.

3. A reinforced concrete structure, including a wall formed of baskets filled with concrete, a column formed of baskets filled with concrete, and girders formed of baskets integral with the wall and the column and also 80 filled with concrete.

4. A reinforced concrete structure, comprising a wall, including a basket having a girder-forming extension upon one side 85 thereof, a column including a basket having a girder-forming extension upon one side thereof, said extensions being in alinement, and concrete filling said extensions and forming therewith a girder connecting said wall 90 and said column.

5. A reinforced concrete structure, comprising a column formed of a plurality of baskets superimposed and filled with concrete, the concrete in one basket uniting through 95 the openings in the bottom thereof with the concrete in the basket below, and a basket having a body portion similar in form to the baskets in the column and having a girder-forming extension integral therewith and 100 filled with concrete to form a girder.

6. A reinforced concrete structure, comprising a wall formed of a plurality of reticulated metal baskets superimposed, each basket being filled with concrete and the concrete of each basket uniting through the openings in the bottom thereof with the concrete of the basket below, and including a basket having a body portion similar to the remaining baskets and having a girder-forming extension integral therewith and filled with 110 concrete to form a girder.

7. A reinforced concrete structure, comprising a wall formed of superimposed reticulated metal baskets filled with concrete, the 115 concrete of one basket uniting through the openings in the bottom thereof with the concrete of the basket below, and baskets having body portions similar to the remaining baskets and having side extensions integral with 120 the bottoms thereof and in alinement with said bottoms to form supports for a concrete floor.

8. A basket for use in reinforced concrete construction, comprising a reticulated metal 125 body portion having open-topped channel-shaped extensions integral therewith and leading from the opposite sides thereof.

9. A reticulated metal basket for use in reinforced concrete construction, comprising 130

an open-topped body portion and an open-topped channel-shaped extension leading from one side thereof, and having its walls formed integral with the walls of the body portion and its interior in communication with the interior of said body portion.

10. A basket for use in reinforced concrete construction, comprising an open-topped reticulated metal body portion, and an ex-

tension integral with the bottom thereof and 10 in alinement with said bottom.

In testimony whereof I have signed my name to this specification in the presence of two subscribing witnesses,

JOHN W. MULDOON,
